Des. 183,227
Patented July 15, 1958

183,227

PLASTIC-BINDING MACHINE

George C. Seeger, Skokie, James K. Duncan, Park Ridge, and John E. Jones, Wilmette, Ill., assignors, by mesne assignments, to American Photocopy Equipment Company, Chicago, Ill., a corporation of Illinois

Application May 28, 1957, Serial No. 46,376

Term of patent 14 years

(Cl. D55—1)

Figure 1 is a right hand perspective view of a plastic-binding machine showing our new design.

Fig. 2 is a left hand perspective view of the machine.

Fig. 3 is a rear elevation view of the machine.

We claim:

The ornamental design for a plastic-binding machine, as shown.
